MAGNETICALLY INFLUENCED ARC DEVICE

William D. Buckingham, Southampton, N. Y., assignor to The Western Union Telegraph Company, New York, N. Y., a corporation of New York

Original application August 10, 1949, Serial No. 109,456. Divided and this application August 4, 1950, Serial No. 177,612

4 Claims. (Cl. 315—343)

1

This invention relates generally to improved means for magnetically controlling arc discharge devices, and more particularly to suitable means for causing the arc stream to maintain a predetermined path between electrodes in concentrated arc discharge lamps of the type described in Buckingham and Deibert Patent No. 2,453,118, and in my copending application Serial No. 83,151, filed March 24, 1949, which operates with a highly concentrated arc discharge in contradistinction to a low pressure diffused or glow discharge, the disclosure of which patent is incorporated herein by reference thereto.

This application is a division of application Serial No. 109,456, filed August 10, 1949, now Patent No. 2,541,028, issued February 13, 1951.

With suitable construction, such as illustrated herein, a concentrated arc device of the foregoing type is particularly adapted for use in high wattage lamps, such as those used in flood lamps, search lights and the like, operating in the open air and powered from a source of alternating current supply. The lamp utilizes two electrodes, which in an alternating current type may be identical in construction if desired, and which alternately operate as anodes and cathodes during each cycle of the alternating current supply which may be the 110 volt, 60 cycle current commonly available. Each of the electrodes may comprise a generally cylindrical metal tube or shell that is closed at one end and is filled with the electrode material. The thin active surface film of the electrode material at the open end of the tube comprises a molten metal, such as zirconium or hafnium, when the lamp is in operation, and underlying this active surface film is an oxide of the metal. This oxide has a melting point much higher than that of the base metal which has high electron emissive properties at the very high temperature at which the device operates, but which is not a sufficiently good electron emitter at lower temperatures to cause the electrons to be emitted in sufficient quantity to support an arc of high current density until the metal has reached incandescent temperatures, well above the melting point of the metal.

Either zirconium or hafnium metal is a better electron emitter at high temperatures than is its oxide, and it also has a lower melting temperature; thus, under the intense ionic bombardment of the arc a very thin molten film of this metal is formed over the active surface area of the electrode, and as soon as it is formed the temperature of the electrode drops slightly and the underlying oxide solidifies and supports the film of molten metal on its surface. It is this thin film of

2

molten metal that is the chief source of the visible radiation from the lamp. It is so thin that surface tension holds it to the oxide backing so that the lamps may be burned in any position.

It is desirable to dispose the electrodes at an angle to each other in order to provide an unobstructed light output from the active surface films thereof. In this case the arc stream between the active surfaces of the electrodes should follow a curved path, but sometimes the arc stream would tend to concentrate on the edges of the electrodes closest to each other, and at other times would tend to rise due to convection currents and also when the arc stream became too long.

An object of the invention is the provision of suitable means for automatically controlling and maintaining a desired position of the arc stream between the electrodes.

Another object is to cause the arc stream to maintain a predetermined path between the electrodes when disposed at an angle to each other thereby to prevent the arc stream from concentrating on the edges of the electrodes closest to each other and also to prevent the arc from rising due to convection currents or other causes.

Other objects and advantages of the invention will be apparent in the following detailed description of two illustrative embodiments thereof, taken in connection with the accompanying drawings in which:

Fig. 1 is a view, in elevation, of a high wattage open air lamp adapted to be powered from alternating current, in which the electrodes are mounted approximately at right angles to each other, with suitable magnetic structure for automatically controlling the position of the arc stream, the figure also showing means for automatically maintaining the correct distance between the electrodes;

Fig. 2 is a fragmentary view of the magnetic structure for controlling the position of the arc stream, taken along the line 2—2 of Fig. 1;

Fig. 3 shows a circuit arrangement for use with smaller sizes of the alternating current lamp with means for automatically controlling the position of the arc stream;

Fig. 4 is a view of a modified arrangement for controlling the position of the arc stream in an alternating current lamp, together with manually operable means for maintaining the electrodes at the correct distance from each other;

Fig. 5 shows a circuit arrangement for operating the alternating current lamp illustrated in Fig. 1, with means for automatically controlling the position of the arc stream, and including

means for automatically maintaining the correct distance between the electrodes; and

Fig. 6 shows a circuit arrangement for controlling the position of the arc stream in the manner illustrated in Fig. 4, together with a modified starting and running circuit for the lamp.

Referring to Fig. 1 of the drawings, there is shown a construction adapted for use with high wattage lamps, capable of operating in the open air and powered from a source of alternating current supply. The lamp utilizes two electrodes 12, which may be identical in construction if desired, and which alternately operate as anodes and cathodes during each cycle of the alternating current supply. The electrodes are disposed at an angle of approximately 90° to each other, as shown in the figure, in order to provide an unobstructed light output from the lamp. The light, which principally comes from the active surfaces 16, passes through a condenser lens 44 and thence through a light aperture 45 and projecting lens 46. Means hereinafter described are provided for rotating the electrodes to insure proper centering of the light spots on the activated surfaces 16 of the electrodes, the arrangement enabling this to be done without having the electrode-rotating mechanism in the field of projection of the light.

The interior construction of each of the electrodes is preferably in accordance with that disclosed in the parent case of which this is a division. The electrode material may comprise zirconium or hafnium metal powder with which is mixed a material that protects all but the active end of the core from oxidation, whereby progressive oxidation of the zirconium or hafnium metal beneath the underlying oxide layer can be prevented. A suitable powdered metal, such as nickel, in the proportion of about one part of nickel to three parts of zirconium metal powder, when zirconium is employed, has been found to produce a mixture which does not progressively oxidize throughout its entire volume as would be the case if zirconium alone was used. Such electrodes acquire only a thin cap of zirconium oxide at the active end, and the underlying conductive nickel and zirconium mixture remains to aid in starting the lamps. Preferably there is also added to the zirconium-nickel mixture a small percentage of a metallic substance, such as magnetite, which is an oxide of iron, the magnetite increasing the electrical conductivity through the fused oxide cap when the electrode is cold, and thus aids in starting. The exact proportions of the metals and oxides in the whole mixture do not seem to be critical. However, if more than 40% of nickel is employed in the mixture, excessive smoking occurs and the electrode erodes away more quickly; if less than 5% of nickel is employed, the protective action of the nickel is not present. With respect to the conductive material, such as magnetite, from 2% to 15% may be employed.

It will be understood that as the electrode slowly erodes during operation of the lamp, that portion of the zirconium which is exposed to the arc does oxidize thereby to maintain the underlying oxide layer, but further oxidation of the mass below the oxide layer does not take place to any substantial extent. The same effect is obtainable when hafnium metal powder is used instead of zirconium metal powder.

Each of the electrodes 12 is mounted in a holder 18 which is carried by a rotatable metal shaft 23. Surrounding each shaft, and in good

electrical contact therewith, is a metal collector block or collar 20 to which is secured, as by soldering or by screws, the external terminals 13 of the lamp. The collector block is secured to an insulating block 21 that is mounted on a slideable block 41, one of the blocks resting on the top surface of a cabinet or supporting frame 50, and the other block 47 being mounted on a vertical side of the structure 50. Each of the blocks carries a motor 26, and the shaft of each motor is connected, by an electrically insulating coupling 34, to the shaft 23 thereby to rotate the associated electrode 12 about its longitudinal axis. The motors 26 may be either direct or alternating current type, and the electrodes are thereby rotated at suitable speeds about their longitudinal axes in opposite directions relative to each other. This speed may be quite low, for example, one revolution per minute, and should not be so high as to cause appreciable centrifugal forces to be exerted on the active surfaces of the electrodes or to cause rotation of the arc spot. A symmetrical oxide bead is thus formed and maintained on each electrode and the position of the luminous spot on each electrode is stabilized.

Fig. 1 also shows means for automatically bringing the electrodes together for starting the arc and for maintaining them at a correct distance from each other during operation of the lamp, which feature relates to divisible subject matter and hence is not claimed herein. The operation is based on a differential action between the arc voltage, i. e., the voltage drop across the arc, and the arc current flowing at any instant. A satisfactory control is obtained by the use of a small two-phase alternating current motor as the balance detecting unit. Each of the blocks 47 has a lug 48 which passes through a slot 49 in the frame structure 50, the lug 48 being internally threaded and receiving a threaded shaft 51, so that rotation of the two shafts 51 in either direction moves the slideable blocks 41 in a direction either to increase or decrease the spacing between the ends of the electrodes. The shafts 51 are geared to each other through bevelled gears 52, and the vertical shaft is driven by the two-phase motor 41 which is controlled in a manner hereinafter described in order to maintain the desired spacing between the electrodes.

It will be seen from Fig. 1 that the arc stream between the active surfaces 16 of the electrodes should follow a curved path, but sometimes the arc stream would tend to concentrate on the edges of the electrodes closest to each other, and at other times would tend to rise due to convection currents and also when the arc stream became too long. In order to prevent this there is provided an electromagnet comprising a coil 54 which is in series with the arc electrodes of the lamp, and an electromagnet 55 which is bridged across the electrodes, these magnets being mounted on an insulating support structure 56 which is secured to the casing 50. The magnet 54, which is the current coil, is wound around a straight core 57 of magnetizable material, and the coil 55 is wound around a U-shaped core of magnetizable material having projecting leg portions 58, as seen in Figs. 1 and 2. The electromagnet 54, which is in series with the electrodes, may comprise for example 200 ampere turns for use with a 750 watt lamp, and the second electromagnet 55 which is connected across the electrodes may have for example 100 ampere turns. The current coil 54 is poled so that its external magnetic field tends to force the arc stream out-

wardly, whereas the voltage coil 55 is poled so that its external magnetic field tends to force the arc stream inwardly and keep the arc from rising. The resultant field maintained by the two electromagnets operates to keep the arc stream centered on each of the active surfaces 16 of the electrodes and cause it to follow the curved path indicated by the broken lines in Fig. 1. Since the magnetic effect of one of the windings is proportional to the current flowing in the arc stream and the magnetic effect of the oppositely poled winding is proportional to the voltage drop across the arc, the resultant effect of their magnetic fields tends to maintain the voltage-current relationship and hence the length of the arc constant.

Fig. 3 shows a starting and running circuit suitable for use with smaller sizes of the concentrated arc lamp in which it is not necessary to rotate the electrodes or to provide means for automatically maintaining the proper distance between the electrodes. When the line switch 60 is closed, current is applied over a circuit comprising conductors 61 and 64 to a high leakage reactance transformer 62 of the constant current type. The transformer shown is an auto-transformer, and conductor 61 is connected to the midpoint thereof so that if 110 volts of alternating current is applied to the primary part of the transformer, 220 volts will be generated across the secondary of the transformer. Bridged across the transformer is a vacuum switch 65, the switch being of the type in which the circuit is made and broken between solid contacts in a vacuum in response to a magnetic field, such a switch having been found to be very effective to provide the surge required in starting concentrated arc lamps of the type disclosed herein. The transformer 62 has an iron core and an open air gap and hence sets up a magnetic field which, when line switch 60 is closed, attracts the magnetizable bar or armature 66 of the vacuum switch, opening the circuit formerly through the switch contacts, the latter circuit including the electrodes 12 of the arc lamp. Various kinds of such switches are well known; one particularly suitable for the purpose is disclosed in my co-pending application Serial No. 35,928, filed June 29, 1948, now Patent No. 2,564,877, issued August 21, 1951, the structure of which enables the switch to be mounted in an aperture in the core of transformer 62. Opening the circuit of switch 65 causes a surge of from 1000 to 2000 volts to appear across the electrodes 12 of the lamp, the surge being due to collapse of the field in the transformer 62, this circuit including a resistor 67 and the winding of electromagnet 54 which is a current coil such as referred to in the foregoing description of Figs. 1 and 2. When the gap between the electrodes 12 breaks down due to the voltage surge, the current flowing through transformer 62 from the supply line 60 maintains the arc across the electrodes and also keeps the contacts of switch 65 open so long as the lamp is operating.

Fig. 5 shows a starting and running circuit similar to Fig. 3 and also discloses a suitable circuit arrangement for the operation of regulating means such as the two-phase motor device 41 in Fig. 1. Connected between one end of the transformer 62 and the electrode terminals is a transformer 70 through which the arc current flows. The secondary winding of the transformer 70 has a variable tap connection 71, the upper end of the secondary winding being connected by 75

means of a conductor 74 to one of the windings A of the two-phase motor, the other end of winding A being connected by a conductor 75 to the right-hand end of the transformer 62. The 5 winding B of the two-phase motor 41 is connected across the supply conductors 61 and 64, a condenser 13 being connected in circuit therewith in order to give a phase displacement so that there will be a suitable phase difference between the currents in the two windings A and B of the motor to provide the necessary starting torque for the motor.

The adjustable contact 71 on the secondary winding of transformer 70 enables the voltage V_1 developed across the winding to equal the voltage V_2 across the lamp terminals at the proper spacing of the electrodes. When voltage V_1 equals voltage V_2 , the two-phase motor 41 has no voltage on one phase represented by its 15 winding A. When the supply current is applied to the lamp through transformer 62 and before the lamp has started, the voltage V_2 is high and voltage V_1 is substantially zero, and the motor 41 rotates in a direction to close the gap between the electrodes until they either touch each other or are sufficiently close to start the arc. The voltage V_2 then drops rapidly, and the voltage V_1 rises rapidly from zero and usually will be greater than V_2 . Under these 20 conditions the motor 41 will operate to separate the electrodes to the correct spacing as previously determined by the adjustment of the contact 71.

If the arc spacing becomes too great, the voltage V_2 increases, and the current through the arc decreases and hence voltage V_1 decreases, so that there is a difference between V_1 and V_2 and this difference causes current to flow through winding A of the motor and causes the motor to 25 rotate in a direction to bring the electrodes towards each other. If the arc spacing becomes too small, the voltage V_2 decreases, and the current through the lamp and also the voltage V_1 increases, and the current flow through winding 30 A of the motor is opposite in phase to that in the previous case when the gap was too long, so that the motor will turn in a direction to increase the separation between the electrodes. The arrangement thus automatically causes the 35 lamp to be started and to maintain the electrodes at their proper spacing during operation of the lamp. The arrangement has substantially linear characteristics which result in accurate control, and there are no overrunning or hunting difficulties involved.

Fig. 4 shows an arrangement in which the position of the arc stream is maintained in a manner such that rotation of the electrodes 12 is unnecessary to maintain proper centering of the incandescent light spots on the active surfaces of the electrodes, and also shows how the desired spacing between the electrodes may manually be maintained. In this modification, the electrode holders 18 have shafts which are received within metal bushings 20 to which the external circuit may be connected, and these bushings are mounted in insulating brackets 16. The brackets are carried by the slide blocks 41, and the positions of the slide blocks and hence the spacing between the electrodes 12 may be 45 adjusted by means of lugs 48 which pass through slots 49 in the supporting structure 50, the lugs 48 being internally threaded and coacting with the threaded shafts 51. The vertical shaft 51 50 may be rotated in either direction by a crank

11 thereby to either advance or retract the electrodes, as desirable or necessary.

12 The current coil 54 (seen in Fig. 6) and the voltage coil 55 are both wound on a straight core 57, Fig. 4, of magnetizable material. The electromagnets are supported by an insulating structure 18 which is secured to the frame or casing 50. Extending from one end of the structure 18 is a rod 19 which has secured thereto a small permanent magnet having its poles 80 disposed at one side of the arc stream, for example, an inch to an inch and a half away from the stream. The two poles of the magnet straddle the arc stream, as seen in the figure, and the external field of the magnet lies in a direction which is transverse to the desired direction of the arc stream. The electromagnets 54 and 55 maintain vertical stability of the arc stream and the permanent magnet maintains lateral stability of the arc stream. The resultant effect causes two closely spaced centers to be maintained in the outer end of the flame in the arc stream and there is much less tendency for the arc stream as a whole either to rise or to fall, and the arc stream does not get too hot in any one place so that disturbing convection currents are not so likely to develop. The arrangement centers the arc stream as a whole so that rotation of the electrodes has been found unnecessary even in the larger size lamps.

13 The permanent magnet 80 may be relatively small in size; for a 750 watt lamp a magnet which is one inch across its pole pieces has been found sufficient to stabilize the arc in conjunction with the electromagnets 54 and 55. It will be understood that the coils 54 and 55 are differentially wound with respect to each other, and since they may be wound on a common core, this substantially simplifies the construction. In Fig. 4, the permanent magnet is shown behind the arc stream, with its legs 80 facing the observer, but the position of the magnet may be reversed, that is, the U-shaped portion may face the observer in which case the legs 80 would be spaced approximately an inch to an inch and a half in front of the arc stream as viewed in the figure. Instead of a permanent magnet 80 an electromagnet may, of course, be employed.

14 The arc lamp of the instant invention may also be used with a direct current source of power, in which case one of the electrodes always operates as an anode. The anode may comprise a plate, rod or other known anode construction and, in fact, may be a solid copper rod which is of such construction as to prevent overheating and vaporization at the point of arc contact.

15 While there are shown and described herein certain embodiments of the invention, many other and varied forms and uses will present themselves to those versed in the art without departing from the invention, and the invention is therefore not limited either in structure or in use except as indicated by the scope of the appended claims.

What is claimed is:

1. An arc discharge device comprising electrodes operating in a gaseous medium at a pressure sufficiently high to cause the discharge between the electrodes to assume the shape of a concentrated arc, and means for maintaining a predetermined stable position of the arc stream comprising electromagnetic structure having two oppositely poled windings whose external magnetic fields influence the arc streams, said electromagnetic structure including a magnetic member having projecting leg portions with the ends

10 thereof positioned adjacent to opposite sides respectively of said arc stream, said windings being operatively connected to the arc circuit so that the magnetic effect of one of the windings is proportional to the current flowing in the arc stream and the magnetic effect of the other winding is proportional to the voltage drop across the arc, the resultant effect of said magnetic fields including the field established by said projecting leg portions tending to maintain the voltage-current relationship and hence the length of the arc constant during operation of the device.

2. An arc discharge device comprising electrodes operating in a gaseous medium at a pressure sufficiently high to cause the discharge between the electrodes to assume the shape of a concentrated arc, and means for maintaining a predetermined stable position of the arc stream comprising electromagnetic structure having two oppositely poled windings whose external magnetic fields influence the arc stream, said electromagnetic structure including a magnetic member having projecting leg portions with the ends thereof positioned adjacent to opposite sides respectively of said arc stream, one of said windings being operatively connected in series in the arc circuit so that its magnetic effect is proportional to the current flowing in the arc stream and the other winding being connected across the arc terminals so that its magnetic effect is proportional to the voltage drop across the arc, the resultant effect of said magnetic fields including the field established by said projecting leg portions tending to maintain the voltage-current relationship and hence the length of the arc constant during operation of the device.

3. An arc discharge device comprising electrodes operating in a gaseous medium at a pressure sufficiently high to cause the discharge between the electrodes to assume the shape of a concentrated arc, and means for maintaining a predetermined stable position of the arc stream comprising electromagnetic structure having two oppositely poled windings whose external magnetic fields influence the arc stream, said windings being operatively connected to the arc circuit so that the magnetic effect of one of the windings is proportional to the current flowing in the arc stream and the magnetic effect of the other winding is proportional to the voltage drop across the arc, another magnet positioned adjacent to the arc stream and having a constant external magnetic field extending in a direction transverse to that of the arc stream, the resultant effect of said magnetic fields tending to maintain the voltage-current relationship and hence the length of the arc constant during operation of the device.

4. An arc discharge device comprising electrodes operating in a gaseous medium at a pressure sufficiently high to cause the discharge between the electrodes to assume the shape of a concentrated arc, and means for maintaining a predetermined stable position of the arc stream comprising electromagnetic structure having two oppositely poled windings whose external magnetic fields influence the arc stream in a direction transverse to that of the arc stream, said windings being operatively connected to the arc circuit so that the magnetic effect of one of the windings is proportional to the current flowing in the arc stream and the magnetic effect of the other winding is proportional to the voltage drop across the arc, another magnet positioned ad-

5 jacent to the arc stream and having a constant external magnetic field which influences the arc stream in a direction transverse to that of the arc stream and in a direction substantially at a right angle to the direction of influence of said two windings, the resultant effect of said magnetic fields tending to maintain the voltage-current relationship and hence the length of the arc constant during operation of the device.
